H. A. Luttgens

UNITED STATES PATENT OFFICE.

HENRY A. LUTTGENS, OF PATERSON, NEW JERSEY.

WHIFFLETREE-COUPING.

SPECIFICATION forming part of Letters Patent No. 257,171, dated May 2, 1882.

Application filed August 29, 1881. (No model).

To all whom it may concern:

Be it known that I, HENRY A. LUTTGENS, of Paterson, in the county of Passaic and State of New Jersey, have invented a new and useful Improvement in Whiffletree-Couplings; and I do hereby declare that the following is a full and exact description of the same, reference being had to the accompanying drawings, and to the letters of reference marked thereon.

10 My invention is an improvement upon a whiffletree plate and clevis for which Letters Patent of the United States of America were granted to me January 1, 1878, No. 198,771.

It consists in an improved mode of fastening the clasp which holds the whiffletree in contact with the pin-formed side of the clevis, which clasp is not fastened to the whiffletree in the same manner as before, but has the form of a cap united to the bars which enter a recess 15 made in the face of the whiffletree. The bars at their ends are united by a cross-bar, which has an opening to receive a bolt. The end of the bolt near its head is shaped to fit this opening, and the bolt-head is reduced in width to that of 20 the bars above mentioned. The bolt itself enters a hole made in the center and bottom of the recess in the whiffletree and passes entirely through the same, being secured by a nut in the rear. By reversing the bolt it can 25 be made to enter the rear of the whiffletree, in which case the cross-bar of the cap is provided with a boss, which forms the nut. A wearing-plate, the same as shown in the original patent, is inserted into the whiffletree, being placed across the recess in the face of the 30 whiffletree; also, a packing-holder with ears to support the whiffletree, similar to that shown in the original patent, is provided with a large cavity for holding the rubber packing.

40 In the accompanying drawings, Figures 1 and 2 are front and rear views of part of a cross-bar and whiffletree of a carriage, united by the improved device. Fig. 3 represents a section through the middle of the same, and 45 Fig. 4 the pin-formed side of the clevis, in section. Figs. 5, 6, and 7 represent the cap, bolt, and wearing-plate in detail, and Figs. 10, 11, 11½, and 12 modifications of the same. Figs. 8 and 9 represent plan and section of the packing-holder.

50 B represents a portion of the whiffletree,

and A a portion of the cross-bar of a shaft to which the whiffletree is secured.

Clevis C is secured to the cross-bar A by bolt l and by screw e', the latter inserted in an 55 elongation of the rear end of the clevis C and below the bolt l.

The packing-holder G is secured to the top of cross-bar A, and is provided with ears m n, which may be bent to suit the position of the 60 whiffletree B. This packing-holder contains a short rubber tube, d', by means of which and the ears m n the whiffletree B is supported.

A wearing-plate, k, is inserted into the face of whiffletree B, which bears against the pin-shaped part e of clevis C. For the purpose of uniform wear, and to avoid ridges forming upon the pin e, it may be made with flattened sides, as shown in Fig. 4.

A washer, w, is inserted into the top of 70 whiffletree B and placed so as to bear against the under side of the upper part of the clevis C. The washer w may be made of Babbitt or anti-attrition metal, and provided with a small oil-hole at the top which does not entirely pass through the washer, or it is made of lignum-vitae, so placed that the end of the grain of the wood acts against the wearing-surface v, provided at the under side of the upper part of the clevis C.

The bars x, x, and y, forming part of cap s, fit 75 into a recess, z, made into the face of the whiffletree B. Bolt a', which enters cross-bar y, passes through the whiffletree B, and is secured by a nut, f, thereby uniting and securing together 80 cap s, pin e, wearing-plate k, and whiffletree B. The slot z is made of such depth as to allow the cap s to be drawn toward the whiffletree. The cap s and bars x, x, and y form together 85 an opening large enough to admit the pin-formed side e of the clevis C, plus the wearing-plate k, and the head of bolt a'. The opening must also be of a size to pass over the end 90 of the clevis C.

To put together the parts which enter the 95 slotted hole in the face of the whiffletree, it is necessary that the difference between the opening within the upper part of clevis C and the width of whiffletree B is at least equal to the thickness of the head of bolt a', plus the thickness of cross-bar y.

The clasp which holds the whiffletree in con-

taet with the clevis, in the manner as shown in the patent above referred to, does not remain firmly secured when in use, nor is it capable of adjustment after being loosened upon the pin by wear or otherwise, which defect is overcome by the peculiar construction of cap *s*, which, by means of bars *x*, *x*, and *y*, extends to the rear of pin *e*, and by bolt *a'* can be readjusted, so as to bear securely upon the pin-formed part *e* of the clevis *C*, thereby enabling the cap *s*, pin *e*, wearing-plate *k*, and whiffletree *B* to remain united by adjustment until the parts are so worn as to become useless.

15 A modification of the mode of connecting the cap *s* and bolt *a'* is shown in Figs. 10, 11, and 11 $\frac{1}{2}$, where that part of cap *s* which is formed by cross-bar *y* is made to form the nut for bolt *a'*, the head of the bolt being placed on the outside 20 and rear of whiffletree *B*. The bolt also may be formed with a conical head, as shown in

Fig. 11 $\frac{1}{2}$; also, if desired, two bolts like *a'* instead one may enter the bars *x* *x*, side by side, in which case the cross-bar *y* may be dispensed with, the bars *x* *x* being made round and enlarged to form the nuts for bolts *a'*; also, washer *z'*, placed and of a shape as shown, may be made of steel tempered so as to act as a spring; also, the wearing-plate *k* may be widened, as shown in Fig. 12, as much as the opening be- 25 30 tween the bars *x* *x* will admit.

What I claim as new is—

In a whiffletree-coupling, the combination of a clevis having the wearing-pin *e*, with the cap *k*, inserted in the face of the whiffletree, adjusting-bolt *a'*, and cap *s*, arranged and operating substantially as set forth. 35

H. A. LUTTGENS.
